CLAIM

We claim the ornamental design for set of nested storage containers with lids and handles, as shown and described.

DESCRIPTION

FIG. 1 is an exploded perspective view of set of nested storage containers with lids and handles showing our new design;

FIG. 2 is a front elevational view thereof;

FIG. 3 is a rear elevational view thereof;

FIG. 4 is a left side elevational view thereof, the right side elevational view being a mirror image thereof; and, FIG. 5 is a top plan view thereof, the bottom plan view being identical thereto.

1 Claim, 3 Drawing Sheets

FIG. 2.

FIG. 4.

FIG. 3.

FIG. 5.
